UNITED STATES PATENT OFFICE.

JOHN B. SEMPLE, OF SEWICKLEY, PENNSYLVANIA.

GUN.

1,218,706.

Specification of Letters Patent. Patented Mar. 13, 1917.

Application filed October 28, 1914. Serial No. 868,975.

To all whom it may concern:

Be it known that I, JOHN B. SEMPLE, residing at Sewickley, in the county of Allegheny and State of Pennsylvania, a citizen 5 of the United States, have invented or discovered certain new and useful Improvements in Guns, of which improvement the following is a specification.

My invention relates to guns of small 10 caliber whose bullets, because of their small size, are incapable of carrying efficient tracers, and consists in combining with such a gun a second gun of such caliber that its projectiles are capable of carrying efficient tracers, and in so coördinating the two guns that they shall range in accord one with another.

The invention has present value in making available to machine-gun operation the 20 benefits which attend the use of tracers, or in superadding to the advantage which the use of tracers affords (that of quickly and surely finding the range of such an isolated mark as an air-craft) the advantages of a 25 machine gun (ammunition of relatively small bulk, light weight, and small cost, and ability to fire a succession of missiles with great rapidity.)

In the accompanying drawing, Figure 1 30 is a plan view of a machine gun combined, according to my present invention, with a gun of larger caliber, and Fig. 2 is a view of the same structure in side elevation.

The machine gun, 1, and the gun of larger 35 caliber, 2, are shown to be mounted on a common standard or base 3, and to be movable therein, that the guns may be trained at will in any direction. It is requisite of the larger gun 2 that its projectiles be capable 40 of carrying tracers—either night or day tracers. A convenient size for this gun is the one-pounder or three-inch gun in common use. With the use of day tracers such a gun may be trained to hit objects in the 45 air at a distance of from one to two thou-

sand yards, and with the use of night tracers a somewhat longer hitting range may be had.

By coupling the two guns together and by firing from the larger gun projectiles 50 equipped with tracers the range may ordinarily be got with four or five shots from the larger gun. When the coupled guns are thus properly trained the machine gun will begin firing its small bullets in sufficient 55 number to obtain hits on the target.

In the matter of coincidence of trajectory, it is possible by proper control of certain variables (firing charge, weight of projectiles, and shape of projectile point) to have 60 the trajectories of the two guns practically identical throughout the effective range. On the other hand, if it is desired to make no compromise in these matters and to maintain the efficiency of both guns, then the 65 interconnection of the two guns may be such that whatever the elevation, the trajectories will at a certain range coincide. And, if desired, further adjusting instrumentalities may be added, to cause that region of substantial coincidence to approach or recede. These are matters well known to the art, 70 and are mentioned here only to indicate the adaptability of my invention to existing conditions.

I claim as my invention:

The herein described method of finding the range of a gun which consists in firing from a second gun mounted to range in unison with the gun whose range is to be found 80 tracer equipped projectiles and changing the direction of the said second gun according to the observations upon the flight of such tracer equipped projectiles.

In testimony whereof I have hereunto set 85 my hand.

JOHN B. SEMPLE.
